UNITED STATES PATENT OFFICE.

FRANK ALLEGREZZA, OF CHICAGO, ILLINOIS.

REMINDER.

Application filed September 8, 1927. Serial No. 218,215.

This invention relates to a reminder, and more particularly to a reminder of the type adapted for use in households, restaurants, etc., for recording from time to time various necessities and supplies to be obtained. Its object is to provide a reminder of simplified and durable construction, which may be cheaply manufactured. It consists in certain features and elements, herein shown and described, as indicated by the claims.

In the drawings:

Figure 1 is a face view or elevation of my improved device.

Figure 2 is an enlarged fragmentary view showing the construction for mounting and supporting the indicators.

Figure 3 is a detail section, taken substantially as indicated at line 3—3, Figure 2.

As illustrated in the drawing, the present invention includes a main mounting member, 10, preferably a metal plate of rectangular outline with the top edge rounded as indicated at 11, for ornamental appearance. The face side of the mounting plate may be coated or finished in any suitable manner to provide a color contrast for a series of itemized lists printed or inscribed thereon. These lists are shown as consisting of general classes and items of food stuffs and household necessities. Adjacent the general classes and items may also be listed specific or related items as sub-classes of a general class, such as indicated in the drawing, the general class, "Baking powder" being shown, for example, with the sub-classes "Soda" and "Yeast" in somewhat smaller size lettering.

These lists are so arranged as to permit the mounting of a movable indicator, 12, near the marginal edges of the plate, 10, opposite each of the general items. The indicators may be provided with pointers of any suitable outline, herein shown in the form resembling a hand with the index finger in pointing posture, and are preferably of sheet metal construction, the wrist portion of the hand being bent around to form a loop as indicated at 13, with the opening extending transverse to the hand. A laterally projecting lug, 14, extends from the loop portion, 13, on the opposite side to and in alignment with the hand proper for manipulating the indicator. The lug, 14, may be made by striking out a partial area from the loop

portion, 13, or by doubling back upon itself 55 a certain amount of the metal plate during the formation of the loop portion.

Two vertically aligned series of lugs, 15, are struck out of the mounting plate, 10, near the vertical margins, with each lug 60 aligned horizontally with one of the items in the adjacent listings. These lugs, 15, project forwardly and horizontally for supporting the indicators, 12, which are rotatably mounted with their looped portions, 13, on 65 vertical rods, 16, each rod being spaced away from the mounting plate, 10, and extending through all the lugs, 15, in one series. The ends of said rods beyond the lugs, 15, are bent at right angles and secured to the 70 plate, 10, as by soldering, as indicated at 17. Thus it will be understood that each of the movable indicators, 12, may be swung about the rod, 16, toward the adjacent item of the list into active reminding position, or 75 may be turned outward into inactive relation. A tap of the finger upon the lug, 14, will swing the indicator part way around and thus facilitate its adjustment to either 80 position.

A thermometer, 18, is mounted on the plate, 10, centrally with respect to the itemized lists, and held in fixed position by tangs, 19, struck out of said plate and engaging the mounting of the thermometer. 85 A calendar, 20, is attached to said plate, 10, adjacent the lower edge, as illustrated. The grouping of the thermometer and calendar with my improved kitchen reminder affords a useful combination, especially welcomed by housekeepers, and therefore particularly for free distribution for advertising purposes. The device when in use is normally mounted in an upright position, and for convenience holes, 21, are provided in 90 the mounting plate, 10, adjacent the upper edge for securing to a wall or the like by any ordinary fastening means.

I claim:

1. In a reminding device of the character 100 described comprising a metallic mounting plate provided on its face with itemized information, outwardly projecting lugs struck out of said plate, each of said lugs being positioned adjacent an item of the information, an upwardly extending rod projecting through said lugs, an indicator including a 105 pointer aligned with each item of informa-

tion, loosely mounted on said rod and supported on the lug adjacent the item aligned therewith, and means on the indicator additional to said pointer for moving the same into reminding and non-reminding positions relative to said aligned item.

2. In a reminder device of the character described comprising a metallic mounting plate provided on its face with a list of itemized information, flat substantially horizontally projecting perforated lugs struck out of said plate adjacent each of the items of the list, a common pivot extending upwardly through all of said lugs in spaced relation to the mounting plate, an indicator aligned with each item, said indicator being formed adjacent one end with a loop for loosely mounting on the common pivot, and slidably supported on the flat upper surface of the lug adjacent the aligned item whereby to permit free movement of indicators into

reminding and non-reminding positions relative to the items aligned therewith.

3. A reminder device of the character described including a metallic mounting plate 25 provided on its face with a list of itemized information, outwardly extending lugs struck out of said plate adjacent each item of the list, a rod extending upwardly through said lugs, an indicator aligned with 30 each of said items, mounted on said rod and supported by the lugs, said indicators each being provided with an outwardly extending lug whereby said indicator may be manipulated into reminding and non-reminding 35 positions with respect to the aligned item.

In testimony whereof I have hereunto set my hand at Chicago this 7th day of September, 1927.

FRANK ALLEGREZZA.
